[57] CLAIM

The ornamental design for a watch holding box, as shown and described.

DESCRIPTION

FIG. 1 is a perspective view of a watch holding box showing my design;

FIG. 2 is a top plan view thereof;

FIG. 3 is a left side elevational view thereof; the right side elevational being a mirror image thereof;

FIG. 4 is a front elevational view thereof; the rear elevational being a mirror image thereof;

FIG. 5 is a bottom plan view thereof;

FIG. 6 is a perspective view thereof, in an open position; and,

FIG. 7 is a top plan view of FIG. 6.

The broken line showing a watch holding apparatus is for illustrative purposes only and forms no part of the claim.
